BLANK HEATING FURNACE

Filed Jan. 30, 1922

Fig. 1.

UNITED STATES PATENT OFFICE.

HARRY C. JOHANSEN, OF CHICAGO, ILLINOIS, ASSIGNOR TO SULLIVAN MACHINERY COMPANY, A CORPORATION OF MASSACHUSETTS.

BLANK-HEATING FURNACE.

Application filed January 30, 1922. Serial No. 532,680.

My invention relates to blank heating furnaces, and more particularly to blank heating furnaces for heating the blanks from which cutter bits are made for use in mining machines of the cutter chain type, or for reheating bits requiring resharpening.

An object of my invention is to provide an improved blank heating furnace. Another object of my invention is to provide an improved blank heating furnace which will provide a constant supply of heated blanks and in which a series of blanks may be gradually brought up to the required temperature for working. A further object of my invention is to provide an improved blank heating furnace provided with heating means of the fuel oil or other hydrocarbon burner type. Other objects and advantages of my invention will hereinafter more fully appear.

20 In the accompanying drawings I have shown for purposes of illustration one form which my invention may assume in practice.

In these drawings,—

25 Fig. 1 is a plan view of the illustrative embodiment of my invention.

Fig. 2 is a view in central longitudinal vertical section on the line 2—2 of Fig. 1.

30 Fig. 3 is a detail viewed from the line 3—3 on Fig. 1.

Fig. 4 is a detail section on an enlarged scale on a plane corresponding to the line 4—4 of Fig. 2.

In the embodiment of my invention which I have shown and shall now describe for purposes of illustration, a heating furnace generally designated 1 together with blank conveying means generally designated 2 is supported upon suitable legs 3 and 4, the furnace proper comprising a combustion chamber 5 which is supported upon a bed plate 6 and is completely enclosed with the exception of certain openings, which will be more particularly referred to hereinafter, by fire brick 7. The combustion chamber has herein a horizontal bottom 8, an inclined top 9, a vertical end wall 10 at the lower end of the top, and a wall 11 at the opposite end made up of a vertical section 12 and an inclined section 13. Within the inclined section 13 is formed a burner receiving orifice 14 over which is secured a suitable oil or other hydrocarbon burner 15 which discharges its blast of burning gases angularly downward along the bottom. The vertical walls 10 and 12 are traversed by openings 16 and 17 of

small size. These openings, of which there may be one or more, (herein two are shown at either end of the furnace combustion chamber) are of just sufficient size to permit the passage through them of the conveyor 2 together with the blanks 19 carried thereby.

The conveying means 2 includes herein a pair of conveyor chains or belts 20 and 21 of which one may be used for heating blanks prior to forging and the other for heating blanks to be tempered, or both may be used for either purpose as desired. In the present case the belt 20 is shown as a preheating conveyor while the belt 21 is shown as a tempering conveyor. These belt or chain conveyors are suitably supported on transverse shafts 23 and 24 arranged at the opposite ends of the frame in suitable bearings 25. The belt 20 is carried upon a chain sprocket 26 pinned, or otherwise suitably fastened, to the shaft 24 and upon a second sprocket 27 freely rotatable upon the shaft 23. The belt 21 is supported by sprockets 28 and 29, of which the former is pinned to the shaft 23, while the latter is freely rotatable on the shaft 24. Suitable driving means for the shafts 23 and 24 are provided, consisting of ratchet wheels 30 and 31 respectively fixed to the shafts 23 and 24, and with these ratchet wheels pawl carrying arms 32 and 33, respectively co-operate, these arms oscillating freely about the shafts 23 and 24 and being moved by connecting rods 34 and 35, respectively. The adjacent ends of the connecting rods are secured to pins 36 and 37 mounted on blocks 38 and 39 which are transversely adjustable across driving disks 40 and 41, as will be apparent from Fig. 3. The disks 40 and 41 are provided with spur teeth 42 upon their peripheries and the disk 41 being positively driven by a shaft 43 causes, by means of the mechanism described, opposite rotations of the shafts 23 and 24. The shaft 43 is provided with a worm wheel 44 driven by a worm 45 on a driving shaft 46 which is journaled in bearings 47 carried on the frame and provided with a driving pulley 48. It will be noted that the conveyor chain or belt is herein made up of links 49 each of which has a socket 50 formed therein to receive a blank or bit. The chains run in grooves formed in the fire brick lining in the bottom of the casing so that the chains are largely protected from the heat and the length of the combustion chamber is made such as to permit the complete

combustion of the fuel just as the lower end of the casing is reached and a vent 51 is provided to permit the escape of the completely burned gases. In order to prevent the injury of the links of the conveyor chain, I have provided a water pan 52 into which the chain dips between the points of leaving and entering the furnace.

The mode of operation of this device will be readily apparent. Let it be assumed that the pulley 48 is being positively rotated at a suitable speed by any usual means not shown. Then by reason of the ratchet construction, irrespective of the direction in which the pulley may be driven, the belts or conveyors 20 and 21 will be caused to travel in opposite directions. The rate of movement of these belts or conveyors can be readily adjusted by means of the blocks 38 and 39 which, being moved towards or away from the centers of the disks 40 and 41, will vary the travel of the ratchet arms 32 and 33 and so will give a wide variation in the speed of travel of the conveyors. Blanks will be inserted in the sockets in the links just as the links are about to enter the combustion chamber and will fall out by gravity at the opposite end as the chain passes around to the bottom of the other sprocket. In heating the blanks preliminary to forging, they enter the furnace at the cooler end and pass along, gradually absorbing more and more heat, both from the flame which passes directly over them and by radiation from the hot fire brick lining. The burner will be noted herein to be located between the conveyor belts. It will be noted that in practice a forging machine can be set at the discharge end of the pre-heating conveyor and a tempering bath at the opposite end of the machine. This will permit cold blanks to be heated, forged, reheated, and quenched, all without any manual transportation and in a convenient sequence.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a blank heating furnace, an elongated combustion chamber, a burner discharging longitudinally of said chamber and toward one end thereof adapted to generate different degrees of heat along said chamber with a maximum at said end, and means for feeding a series of blanks longitudinally of said chamber and discharging the same adjacent said end.

2. In a blank heating furnace, an elongated combustion chamber, a burner discharging longitudinally of said chamber and toward

one end thereof adapted to generate different degrees of heat along said chamber with a maximum at said end, and conveying means for carrying a series of blanks longitudinally of said chamber and discharging the same adjacent said end.

3. In a blank heating furnace, an elongated combustion chamber, a burner discharging longitudinally of said chamber and toward one end thereof adapted to generate different degrees of heat with the maximum at said end, and conveying means for carrying a series of blanks longitudinally of said chamber to discharge the same adjacent said end in such a manner that only certain portions of said blanks are exposed to the direct heat of combustion.

4. In a blank heating furnace, an elongated combustion chamber, a burner discharging longitudinally of said chamber and toward one end thereof adapted to generate different degrees of heat along said chamber with a maximum at said end, the top wall of said combustion chamber being provided with a flue opening adjacent said end, and means for feeding a series of blanks longitudinally of said chamber to discharge the same adjacent said end.

5. In a blank heating furnace, a combustion chamber, a burner discharging therein in a longitudinal direction thereof, said combustion chamber tapering in the direction of said burner discharge, and a blank conveyor running through said combustion chamber and conveying the blanks therefrom adjacent the smaller end thereof.

6. In a blank heating furnace, a combustion chamber, a burner discharging therein in a longitudinal direction thereof, said combustion chamber tapering in the direction of said burner discharge, and a blank conveyor running through said combustion chamber and conveying the blanks therefrom adjacent the smaller end thereof, said conveyor being automatically operative to discharge blanks carried thereby after they have left said combustion chamber.

7. In a blank heating furnace, a combustion chamber, a plurality of blank conveyors running longitudinally of said combustion chamber, and a burner discharging longitudinally of said chamber between said conveyors.

8. In a blank heating furnace, a combustion chamber, a plurality of blank conveyors running longitudinally of said combustion chamber in opposite directions, and a burner discharging longitudinally of said chamber.

9. In a blank heating furnace, a combustion chamber, a plurality of blank conveyors running longitudinally of said combustion chamber, and a burner discharging longitudinally of said chamber between said conveyors, said combustion chamber having an inclined baffle wall approaching said conveyors at the discharge end of said furnace

and directing the flame onto blanks disposed on said conveyors.

10. In a blank heating furnace, a combustion chamber having sloping end and top portions, a burner carried by said end portion and discharging longitudinally of said sloping top portion, and a plurality of conveyors

running longitudinally through said chamber adapted to convey a series of blanks through said chamber respectively towards 10 and away from said burner.

In testimony whereof I affix my signature.

HARRY C. JOHANSEN.
